(57) **CLAIM**

I claim the ornamental design for a display screen with animated user interface, as shown.

DESCRIPTION

FIG. 1 is a front view of a first image of a display screen with animated user interface;

FIG. 2 is a front view of a second image thereof; and,
FIG. 3 is a front view of a third image thereof.

The broken lines showing a display screen and elements of a graphical user interface illustrate portions of the article and form no part of the claimed design.

The appearance of the transitional image sequentially transitions between the images shown in FIGS. 1-3. The process or period in which one image transitions to another image forms no part of the claimed design.
